UNITED STATES PATENT OFFICE.

URBAN F. DURNEE, OF MILWAUKEE, WISCONSIN.

DOOR ATTACHMENT.

1,369,270.

Specification of Letters Patent. Patented Feb. 22, 1921.

Application filed May 17, 1919. Serial No. 297,922.

To all whom it may concern:

Be it known that I, URBAN F. DURNEE, a citizen of the United States, residing at Milwaukee, in the county of Milwaukee and 5 State of Wisconsin, have invented certain new and useful Improvements in Door Attachments, of which the following is a description.

My invention belongs to that general class 10 of devices known as doors, and relates more particularly to an attachment for use on doors, whereby one at one side of a closed door can observe and converse with one at the other side of the door without first requiring the opening of the door. The invention has among its objects the production 15 of a device of the kind described that is simple, convenient, durable, ornamental efficient and satisfactory for use wherever found applicable. It has especially as an 20 object the production of a device which when applied to a door will afford security and safety, as well as being convenient and preventing annoyance. Many other objects 25 and advantages of the construction herein shown and described will be obvious to those skilled in the art from the description hereafter given.

To this end my invention consists in the 30 novel construction, arrangement and combination of parts herein shown and described, and more particularly pointed out in the claims.

In the drawings, wherein like reference 35 characters indicate like or corresponding parts,

Figure 1 is a perspective view of a portion of a door equipped with my device;

Fig. 2 is a view in elevation of a portion 40 of the door and my device;

Fig. 3 is a sectional view taken substantially on line 3—3 of Fig. 2;

Fig. 4 is a sectional view taken substantially on line 4—4 of Fig. 2;

Fig. 5 is a sectional view taken substantially on line 5—5 of Fig. 4;

Fig. 6 is a sectional view taken substantially on line 6—6 of Fig. 2;

Fig. 7 is a sectional view similar to Fig. 4 50 illustrating a slightly modified form of device;

Fig. 8 is a view illustrating a modified form of plate and sleeve; and

Fig. 9 is a sectional view illustrating a 55 modified form of hinge construction.

Referring to the drawings, 1 represents

any type of door, whether in dwelling, apartment, office, hotel, institution, or the like, and regardless of whether an outer door or an inner door. I have not considered it necessary to illustrate the details of the door construction proper, as this varies in different types of doors, and depends upon the use to which the door is to be put as well as the materials out of which it is made. It is sufficient, however, to say that my device is applicable for any door regardless of the use to which it is to be put or its construction.

The device in its broadest sense consists of an attachment which may be applied to the door, the door being provided with a small opening of the preferred size and shape at a desired point. When my device is closed, all the privacy and security of the usual door is obtained, but observation may be made and conversation carried on to the satisfaction of the one at the inner side of the door with perfect security and as conveniently as if the door had been opened. The preferred construction consists of an inner frame or the like arranged at the inner side of the door, the same carrying a closing member or what may be termed a small sight door of opaque material, which may be opened to permit observation and conversation. I also employ a slide or second door member arranged to permit observation, and which may be raised to facilitate conversation, or the passing of a card, telegram, receipt or money or the like through to the one on the inner side or vice versa. Referring to the drawings, 2—3 represent a frame which may be constructed as desired, as shown, in two parts or plates, the same being secured in place by screws 4 or their equivalents for the purpose. The plates may be cast, stamped, cut, or otherwise constructed. One of the plates, as shown, 3 is provided with an opening 5 of the desired size and shape, which may be normally closed by the sight door member 6, which is arranged to completely close the opening.

In the construction shown, the sight door 6 is formed with extending parts 7 which serve as hinge members and extend into the grooves 7 (see Fig. 6), these being normally maintained in place by the resilient straps 8 or their equivalents, which also act to shut and maintain the sight door 6 closed. The other plate or frame part 2 is preferably cut out at 9 as indicated in Fig. 5, but provided with extending parts or stops 10. Ar-

ranged in the frame part or plate 2 is a slide frame 11, which is preferably provided with a transparent pane or panel 12 of glass or equivalent material, which may if desired be secured in place by the member 13 or its equivalent for the purpose. The slide frame part 11 is provided with the extending lugs 14 arranged to engage with the stops 10 and prevent the slide or frame 11 from being entirely and accidentally removed, so that the same cannot become mislaid or lost. It also prevents it being entirely removed and perhaps accidentally dropped, in which case the glass panel or its equivalent might be injured. Any suitable means may be provided for operating part 11. As shown, I provide the extending part 15 for this purpose. I have shown the door part 6 provided with a pin 16, which may be split at the end as shown, and is of a length to extend into the opening 17 in the slide 11. As shown, the pin 16 is carried by a part 18 secured to the door, and extends through the frame part 3 (see Fig. 4), 19 being a knob 25 for opening the door and at the same time withdrawing the locking pin 16, so that the slide 11 may be raised if desired. The pin 16 thus locks slide 11 closed, and as a result the inner door 6 cannot be manipulated and 30 opened from the exterior side of the door 1. At the outer side of the door I provide a plate or frame part 20, which may be secured in place by screws 21 or their equivalent for the purpose. Formed separately or 35 integrally with one of the plates, as shown, integrally with plate 20, is a sleeve part 22 of a size to fit the opening cut in the door, thereby improving the appearance of the device as well as making the opening the 40 exact size desired. I have shown a sleeve part 22', which may be employed instead of extending part 22 entirely through the opening. The sleeve part 22' may be the desired size for the particular door, but if 45 too large may be cut down to fit or adjusted. I have shown a plate 2', the purpose of which is to prevent the sliding frame 11 from marring the door, and it also causes it to slide easier. Its use, however, is not essential. 50

A slightly modified construction is shown in Fig. 7 in which 23 represents the door and 24 the plate on the exterior of the same, which in this case is also formed with a 55 sleeve 25. In this construction the sight door 26 corresponding to the door 6 is shown on the exterior side of the door 23, the same being pivotally hinged or supported at 27 in any suitable manner. A latch 28 arranged to engage lug 29 or equivalent means 60 may be provided for locking the small door shut, and I have shown the spring 30 tending to normally maintain the latch in locking position. In this case 31 represents a 65 frame at the inner side of the door, 32 the

slide and 33 the transparent pane. Fig. 8 is intended to illustrate how the plates at the inner and outer sides of the door may be secured together by common means, and in such a manner that a plate at the exterior side cannot be easily removed. Referring to this figure, 34 represents the outer plate and 35 the sleeve, while 36 represents screws or bolts which may take the place of the screws 4 previously described, but which extend through and engage the threaded lugs 37 or the equivalent, thereby securing the two plates together. 70

In Fig. 9 is illustrated a modified construction for securing the small sight door in place, in which case 38 represents the door corresponding to door 1, and 39 the sleeve through the door opening, while 40 and 41 represent the equivalent of the plates 2 and 3 shown in Figs. 3 and 4 in the preferred construction. 43 represents the slide provided with the glass panel 42, and 44 a small sight door corresponding with door 6. In this case door 44 is secured to frame 41 by a pin 45, 46 being a coil spring so arranged as to tend to throw the door 44 shut and maintain it in its closed position. 80

While it will be obvious that my attachment may be made in various sizes, I prefer to make the same substantially of the size shown, which is amply sufficient for the purpose of conversation or observation, or for the passing through of a card or small article, and still of such sizes that one at the outside cannot extend a hand through the same. By providing the doors with shutters, greater privacy is obtained in the interior, and it is not possible for one to reach in by means of instruments and manipulate the door lock or knob. When one at the outside 100 approaches and by means of the door bell, telephone or knocking, or otherwise attracts the attention of the one at the inner side of the door, the one on the inner side may open the sight door 6 or its equivalent and observe 105 who is without. If desired they may converse through the glass, but ordinarily it is preferred to raise the slide, especially if the one from the outside desires to pass a card to the one within or vice versa. There is no 110 chance for the one without entering until the door is opened. Without my device it would be necessary, in order to see the one without, to open the door, in which case the one from without might place a foot, cane or something else in the crack of the door, thereby preventing the occupant or one at the inner side from closing the door. This is even true with chains or bolts, as the door can be 115 prevented from being fully closed by the one at the outer side. The device is therefore particularly desirable in residences, apartment buildings and the like. It is also desirable for the same reasons in hotels, each 120 room door being equipped with one of the 125

130

devices. The same is also convenient as the one within can observe who is without and converse even if not entirely clothed or otherwise not presentable. The one from without likewise is not able to make any observation of the interior of the room, as the sight door 6 may be only partially opened a sufficient distance to satisfy the one at the inner side. The device is especially attractive as well as convenient and safe. In apartment buildings, while they are generally equipped with 'phones or speaking tubes, and peddlers, tramps and others are supposed to be kept out of the interior halls by outer doors, these people frequently gain admittance to the interior halls, in which case the one within the apartment having doors equipped with my devices can always first observe who is outside before opening the door, as well as converse if it is not desired to open the door.

Having thus described my invention, it is obvious that various immaterial modifications may be made in the same without departing from the spirit of my invention; hence I do not wish to be understood as limiting myself to the exact form, construction, arrangement and combination of parts herein shown and described, or uses mentioned.

What I claim as new and desire to secure by Letters Patent is:

1. In a door attachment of the kind described and in combination, plates arranged to be placed on the exterior and interior of the door, a two part tubular sleeve arranged between said plates, a sight door member pivotally carried by one plate for normally closing the opening through said sleeve, and a transparent shutter slidably arranged between said plates adjacent the sight door, and means carried by the sight door for locking said transparent shutter in position.

2. A door attachment of the character de-

scribed, comprising supporting means located at one side of the door, a sight door movably attached to said supporting means, a transparent shutter located adjacent the sight door and adapted to be maintained in position for a movement, said sight door and shutter being capable of independent relative movements, and means carried by the door for locking the shutter in a closed position.

3. An attachment of the character described, comprising supporting means adapted to be secured to a door adjacent an opening therein, a sight door carried by said supporting means at one side of the opening, a shutter adjacent said sight door at the same side of the opening as the sight door, said shutter and sight door being capable of independent movements, and means carried by the sight door and coöperating with the shutter for maintaining the shutter in a closed position.

4. A door provided with an opening therethrough, an adjustable tubular sleeve arranged in and closely fitting said opening, plates arranged on the inner and outer sides of the door at the ends of said sleeve, and provided with openings to permit observation through the door, a sight door arranged at the opening through the inner plate, resilient means, for retaining said sight door closed, a transparent shutter slidably arranged between said sight door and the sleeve, and means carried by said sight door for locking said shutter against movement when the sight door is closed.

In testimony whereof, I have hereunto signed my name in the presence of two subscribing witnesses.

URBAN F. DURNER.
